WAVE SIGNALING SYSTEM.

Application filed February 23, 1927. Serial No. 170,179.

This invention relates to high-frequency amplifying systems, especially to such systems comprising several tuned stages, each stage including an electron discharge device 5 hereinafter referred to as a "vacuum tube", and has for its principal object the provision of means for attaining high amplification, or gain, with simplicity of control, and freedom from undesirable oscillations and signal 10 distortion.

It is well known that tuned high-frequency multistage vacuum tube amplification systems are inherently unstable and liable to oscillate because of undesired capacitive and 15 magnetic couplings between portions of the respective input and output circuits. When but one or two stages of high-frequency amplification are employed, this tendency toward oscillations can be minimized or eliminated by various expedients; but the necessity for the provision of greatly increased 20 high-frequency amplification, as by employing more than two highly efficient amplification stages, has presented several distinctly 25 new problems, of which a satisfactory solution is realized in the present invention. Radio receivers including a multistage high-frequency vacuum tube amplifier embodying the improvements introduced by the present 30 invention, and of the type hereinafter described, will afford the following advantages: (1) complete freedom from undesirable oscillations and signal distortion resulting in faithful amplification; (2) a high degree of 35 amplification, or gain, per stage; (3) freedom from signal pick-up by the component electrical units or elements and wiring, except through the antenna or antenna input circuit; (4) substantially uniform high-frequency 40 amplification throughout the entire operating frequency range of the system; (5) not necessarily more than two manual tuning controls, regardless of the number of tuned circuits; (6) good selectivity without 45 critical tuning adjustments; (7) complete volume control independent of tuning adjustment and without sacrifice of fidelity of amplification; and (8) convenient physical size, and arrangement of components where- 50 by the overall dimensions of the cabinet are minimized.

These advantages, while of independent merit, are, in general, nevertheless, the result of mutually dependent and correlated means 55 cooperating to effect a substantial improve-

ment, as will be observed from a consideration of the following description of a preferred embodiment of this invention illustrated in the accompanying drawings, in which

Fig. 1 is a front-of-panel view of a complete radio receiver to which the several features of the present invention have been applied;

Fig. 2 shows a top view of the same receiver, with the cover removed, and illustrates the physical arrangement of the principal component parts;

Fig. 3 is a diagrammatic representation of the circuit arrangement of the radio-frequency stages and detector shown in Figs. 1 and 2;

Fig. 4 represents graphically typical resonance curves, or tuning characteristics, of the sharply tuned, and of the broadly tuned high-frequency amplifying stages;

Fig. 5 represents graphically the voltage amplification per stage of high-frequency transformers, (a) as employed previous to the present invention, and (b) in accordance 80 with the present invention.

Referring especially to Figs. 1 and 2, there are illustrated two views of a radio receiver completely enclosed within a cabinet of convenient proportions. This cabinet contains a metal box divided by metallic partitions 5, into five separate compartments numbered from left to right (1) to (5), inclusive, which in effect are five compartments electrically bonded together.

Each of the first three compartments completely encloses an individual high-frequency amplification stage, and because each compartment resembles a box, it is herein termed a "box shield". The joints of each compartment or box shield should be soldered, welded, or crimped mechanically, in order to eliminate all possibility of leakage of magnetic flux. The top of each box shield has an opening 50 therein, through which a vacuum tube such as V_1 may readily be inserted or removed from the vacuum tube socket VS_1 within the compartment. The vacuum tubes may partially protrude through the openings 50 so that they may be easily grasped for removal from the receiver. Metal covers 51 close the openings against stray couplings.

In Fig. 2, the first compartment, or box shield on the left, numbered (1), is indicated as containing an antenna inductance T_1 , an

adjustable tuning condenser C_1 and a vacuum tube socket VS_1 . These three components, together with a suitable vacuum tube V_1 , may be considered to comprise the first 5 tuned stage. The compartments numbered (2), (3) and (4) are substantially identical with each other, and, similarly, they each contain a tuning condenser C_2 , C_3 and C_4 , respectively, an interstage transformer T_2 , T_3 and T_4 , respectively, and a vacuum tube socket VS_2 , VS_3 and VS_4 . Compartment 10 (5), at the extreme right, contains low- or audio-frequency apparatus and therefore need not be completely shielded. Compartment (5) is indicated as including a vacuum tube socket VS_5 for the first low-frequency amplifying tube, and a second socket VS_6 for the second low-frequency amplifying tube. The first low-frequency tube V_5 is intended to be coupled to the output circuit of 15 the detector tube V_4 by means of low-frequency transformer T_a . Likewise, the second low-frequency tube V_6 is coupled to the first low-frequency tube by means of transformer T_{a1} . It will be noted that the first 20 tuning condenser C_1 is fastened directly upon the control panel 24, and is independently adjustable by a manual control 21. The three additional tuning condensers, C_2 , C_3 and C_4 , were, in the actual receiver illustrated, 25 mechanically secured to the frame of the containing cabinet; although, of course, any other convenient means of support could be provided. These three condensers are advantageously arranged with their rotatable 30 shafts 19 parallel to the plane of the control panel, and with their ends abutting and coupled together with a suitable metal coupling, or alternatively, the rotors of condensers C_2 , C_3 and C_4 may be mounted on a single metal rod or shaft. These condenser 35 rotors are thus electrically connected together through the shaft 19 common to the three condensers. The shaft is rotated through a 40 right-angle mitre gear 18 by manual control knob 20. By means of this arrangement all tuning condensers of the stages other than the first may be adjusted simultaneously by the single control knob 20. The arrangement 45 described thus limits the number of tuning controls to two, regardless of the number of tuned high-frequency stages. The present invention introduces this simplicity of tuning controls by reason of the provision that the first, or antenna, stage shall be sharply 50 tuned, and the subsequent high-frequency stages shall be broadly tuned with respect to the first stage.

It is well recognized that the coupling of 55 several high-frequency tuning condensers for simultaneous control by a single adjusting device introduces many manufacturing difficulties, one of the most important of which is the requirement that a given annular change of the control shaft shall effect an

exactly equal capacity change in all of the coupled condensers. When it is required that all of the high-frequency amplification stages have a sharp resonance characteristic, and be controlled by a single adjusting device, the 70 tuning condenser individual to each stage must necessarily be manufactured with extreme precision. Experience has shown that the cost of manufacturing such condensers, and subsequently assembling them in an amplifier, is so great as to be almost prohibitive in the manufacture of commercial radio receivers. This invention, by providing an extremely sharply tuned first stage of high-frequency amplification individually controlled, followed by several stages of tuned high-frequency amplification, all of which are tuned more broadly than the first, and adjustable together by a single control, results in a radio receiver having good selectivity with but two tuning controls, regardless of the number of tuned amplification stages. Another disadvantage formerly introduced by employing a single shaft for the tuning condensers is that this common metal shaft normally forms a closed loop with the shaft bearings and metal shield of the amplifier as a whole which frequently caused oscillations due to stray couplings with some other closed circuit of the amplifier, such as 95 a loop antenna circuit. The present invention likewise overcomes this disadvantage.

Referring again to Figs. 1 and 2, the dotted lines indicated at 5 represent the vertical walls of the box shields separating and 100 electromagnetically isolating the several stages. The voltmeter shown upon the front panel of the receiver, and here included within compartment 3, may be so connected that it indicates at will the voltage of either the low- or 105 the high-tension current supplied to the receiver. Rheostats R and R' , upon the control panel 24, are adjusted by means of knobs 22 and 23, respectively, to control the filament current of the vacuum tubes. Rheostat 110 R is arranged to control the filament current of the high-frequency amplifying tubes simultaneously, while rheostat R' is arranged to control the filament current of the 115 detector tube V_4 alone. Because of the fact that vacuum tube detectors function most effectively with a certain critical filament current it is desirable that the detector filament be independently controlled. On the other hand, high-frequency amplifying tubes are 120 not critical as to their filament temperature and may be conveniently controlled by a single rheostat. By providing the separate control rheostat for the filaments of the high-frequency amplifier tubes, the present invention introduces a distinct advantage in that the high-frequency amplification, and consequently the output, or degree of final amplification, may thereby be conveniently controlled from zero to maximum without in any 125 130

way affecting the tuning adjustment. It is sometimes desirable, however, that the filament of but one of the high-frequency amplifier tubes be separately adjustable for volume control. This complete control of the high-frequency energy is made possible by the present invention through the provision of substantially total capacitive and electromagnetic isolation of the separate stages, except for the desired interstage coupling; the only energy which can pass through the amplifier as a whole being that which is transferred by virtue of the thermionic action of the vacuum tubes, and the desired coupling through the transformers. Hence, regulation of the filament current in any high-frequency stage effects an absolute control from zero to maximum of the energy passed on to a succeeding stage, without affecting the tuning adjustments of the amplifier, and without introducing signal distortion.

Fig. 3 is a circuit diagram of the high-frequency amplifying and detector portion of the receiver herein illustrated and described. The low-frequency amplifier shown in compartment (5), Fig. 2, has been omitted from the diagram of Fig. 3 inasmuch as the low-frequency amplifier is not an essential feature of the present invention. It is assumed that any suitable low-frequency amplifier may be connected to the terminals marked "Output" in Fig. 3; and that a suitable indicating device such as a loud speaker may be connected to the low-frequency terminals marked "Output" in Fig. 2. Fig. 3 illustrates several features of the present invention which are best shown by means of a circuit diagram, and which, for simplicity, were omitted from the preceding figures. It will be noted that the high-frequency stages (1), (2) and (3) include neutralizing coils 7, 10 and 13, respectively, one such coil being connected in series with a capacity between the grid electrode and the filament system of each high-frequency amplifying tube in accordance with the invention described in Hazeltine Patents Nos. 1,489,228 and 1,533,858. As has been previously suggested, the provision of a plurality of efficient high-frequency stages introduces so strong a tendency toward undesirable oscillation, due to the high degree of amplification, that extreme precautions must be taken to avoid interstage couplings. For convenience, it is customary to employ a single current source of low voltage for the several tube filaments, and a single current source of high voltage for the plate electrodes of the several tubes. The five binding posts marked (-C), (+C), (-A-B), (+6) and (+90) are intended to be connected to appropriate voltage sources. The 90-volt connection supplies the plate circuits of the amplifier stages and of the detector, and the 6-volt connection supplies the filament voltage for all tubes, the negative terminals

of the sources of both voltages being connected together on the (-A-B) binding post. The posts marked (-C) and (+C) are intended to be connected in series with the return leads from the grids to the filament systems of both low-frequency amplifier tubes V_5 and V_6 , of Fig. 2, in the customary manner, so as to place a suitable negative voltage upon the grids of those tubes. The (-C) binding post is shown not connected in Fig. 3, because compartment (5) has been omitted from that figure.

Such common source of potential, whether it be batteries, generators, or other source, introduces an impedance common to all of the stages to which it is connected. This impedance is frequently sufficient, in the case of a multistage highly efficient amplifier such as that herein described, to cause undesired oscillations. It will be noted that the present invention provides for complete electromagnetic and electrostatic isolation of each high-frequency stage; and it appears that when three or more high-frequency stages are employed, all of the means provided by this invention are usually required to prevent oscillations. By completely enclosing each individual high-frequency stage, including its vacuum tube, within a box shield, substantially all of the undesired interstage electromagnetic and stray capacitive coupling is eliminated. The capacitive coupling between the input circuit and the output circuit of each vacuum tube is neutralized as described in the Hazeltine patents referred to. A by-pass condenser C_p is provided in each stage connected directly from the low-potential terminal of the primary winding of each high-frequency transformer T_2 , T_3 and T_4 , directly to the filament of each tube, respectively, in order to provide a low-impedance high-frequency return path from the plate electrode to the filament of each tube. A non-inductive resistance R_2 , R_3 and R_4 , is connected respectively in the plate or output circuit of each high-frequency amplifying tube between the plate inductance and the plate-circuit battery to force the plate-circuit currents to return to the filament through the by-pass condensers C_p , C_{p2} , C_{p3} and C_{p4} . In order that the entire filament system may be at ground potential with respect to all portions of the high-frequency circuits, a high-frequency choke coil, L_1 , L_2 , L_3 and L_4 , is inserted in series with the ungrounded lead for the filament current supplied to the respective tubes. Any high-frequency potentials which tend to build up on either side of these choke coils are reduced by means of by-pass condensers C_{t1} , C_{t2} , C_{t3} and C_{t4} , together with condensers 16 and 17. By bonding all of the box shields with low-resistance electrical connections, and by connecting one terminal of the filament of each vacuum tube to the grounded shield, the en-

tire filament system is reduced, at high frequencies, to ground potential.

In completely shielded receivers employing a common metal shaft to operate the several tuning condensers, there may be produced harmful stray currents which serve to couple non-adjacent stages. This effect may be eliminated either by dividing the shaft into insulated sections, or by grounding the shaft electrically at the several points (Fig. 2) where it passes through the walls of the box shields. These ground connections serve to short circuit in several places the electrical loop which otherwise would be formed by the metal condenser shaft, the end bearings and the shield as a whole.

The detector, or rectifying tube, V_4 , is connected in the usual manner. Compartment (4), in which this tube is located, includes in addition, a non-inductive resistance R_5 connected in series with the detector plate electrode. This resistance is inserted primarily to prevent high-frequency currents from flowing through the batteries, but it also incidentally reduces the 90-volt supply to a lower voltage suitable for the output circuit of the detector tube. By-pass condensers, C_{p5} and C_{p4} , are connected, between the grounded shield and one side, respectively, of resistance R_5 to assist in preventing high-frequency current from flowing through the detector output circuit.

It will be noted that a tuning condenser, C_1 , C_2 and C_3 , is connected across the terminals of the input inductance, T_1 , connected between the grid and the filament of each of the high-frequency amplifying tubes. In like manner the input circuit including inductance 14 of detector tube V_4 is tuned by means of condenser C_4 . The customary grid condenser C_g and grid leak R_g are connected in the grid circuit of the detector tube in order to maintain the grid electrode at a suitable operating potential with respect to the filament. Each of the tuning condensers after the first may be connected in parallel with a small adjustable condenser, indicated, respectively, in Fig. 3 by reference characters C_{a2} , C_{a3} and C_{a4} . The purpose of these auxiliary condensers is to determine the minimum capacity value of the tuning condensers which are adjusted by means of the common shaft. Small manufacturing variations in the tuning condensers, in the inductance coils and in the wiring may thus be compensated once for all. A given amplifier or radio receiver, after assembly, should be so adjusted by means of these small condensers that the component uni-controlled circuits are in resonance at the high-frequency end of the operating frequency stage. If the inductance of all of the coils is substantially the same, this condition will be maintained over the entire range, inasmuch

as the capacity of the main tuning condensers is increased uniformly.

It has been found that, in spite of the precautions taken to avoid all forms of undesirable coupling between stages as described, there is sometimes observed a tendency toward oscillations, especially at the higher frequencies of the operating frequency range of the amplifier. In order to obviate this unstable condition recourse has been made to the invention of W. A. MacDonald, for which a United States patent application, Serial No. 85,615, was filed February 3, 1926. In accordance with that invention, the grid connection of the first high-frequency amplification stage is tapped on to the input inductance of that stage at a suitable point, usually found to be near the electrical center of the inductance. Such an arrangement is illustrated in Fig. 3 where the grid connection of the first amplifying tube V_1 is represented as being connected to the center of inductance coil T_1 . The tuning condenser C_1 is connected across the extreme terminals of inductance T_1 , and is employed to sharply tune the first stage input circuit independently of the succeeding circuits of the amplifier. One of the important factors contributing to instability in highly efficient amplifiers is the commercial variation in the plate grid capacity of vacuum tubes. According to the MacDonald invention referred to, the input circuit impedance between the grid and the filament is reduced to a value sufficiently small to prevent certain detrimental voltages due to the mentioned unavoidable couplings from being built up in the grid circuit. For the same reason this expedient provides a satisfactory "tube-capacity tolerance." While it is usually desirable to connect the antenna, if it be of the loop type, or of the open type of short length, directly to the grid of the first tube, as represented in Fig. 3, it may, of course, be coupled to that tube through more or less turns of auto-transformer coil T_1 , or coupled electromagnetically by means of a separate transformer winding, or through a condenser, or by any other desirable means.

Radio receivers embodying this invention are peculiarly well adapted for use in connection with a loop antenna, first because of the high amplification thus made possible, and second because the complete shielding eliminates all possibility of reactions between the inductive loop and parts of the receiver. Inductance T_1 , in Fig. 3, may alternatively be considered to represent such a loop antenna, tuned by condenser C_1 connected across its terminals. In that event the inductive loop T_1 would be operated in the customary manner outside the box shield (1), and, of course, the antenna A , and in most cases the ground G , would be disconnected.

The resonance curves shown in Fig. 4 are

representative of the sharpness of tuning (a) in the first stage, and (b) in the successive stages of high-frequency amplification. It should be understood that these curves are given merely by way of example to illustrate graphically the source of certain of the features of this invention, which are: first, a sharply tuned first stage separately tunable by a single control; and second, a plurality of subsequent stages simultaneously tuned broadly with respect to the first stage, by a second single control. Curve "A" in Fig. 4 shows graphically the tuning characteristics of the first high-frequency amplification stage of a receiver designed and built according to the provisions of the present invention. This curve indicates that the first stage is tuned as sharply as possible without impairing the quality of the received signals through "cutting of the side bands." It is now generally agreed by those skilled in the art, that the amplification of the received oscillations must not be reduced more than fifty percent (50%), within a frequency band eight thousand (8000) cycles wide, or four thousand (4000) cycles each side of the resonance peak, if satisfactory audible reproduction of the receiver signal energy is desired. Resonance curve "A" of the first stage should, therefore, be understood to represent the tuning characteristics of a stage designed to have a very sharp resonance characteristic, but with the foregoing limitation in mind. Obviously, it could be so designed as to have any other desired characteristics obtainable within the known engineering limitations of the art. The sharp tuning characteristic may be obtained by employing in the first stage apparatus which is very efficient at high frequencies, i. e. so that the high-frequency resistance is extremely low. An efficient loop antenna, connected directly in the first stage input circuit, or a short antenna of the open type loosely coupled to T_1 , tuned with an efficient condenser and a low-resistance coil will, in general, result in a resonance curve at least as sharp as that shown at "A." Specifications for a suitable coil are given herein-after.

Curve "B" of Fig. 4 represents graphically the resonance curve of each and any of the high-frequency amplification stages subsequent to the first. These subsequent stages may, within allowable manufacturing tolerances, be identical with each other because each is preceded and followed by a vacuum tube. It is plain that the first stage, electrically, is inherently different from the others because it is not preceded by a vacuum tube. As previously explained, it is impracticable to manufacture the tuning condensers and coils sufficiently alike to enable each of these stages to have a resonance curve as sharp as that indicated by reference character "A". The inductance and capacity ele-

ments of these stages are therefore purposely designed to tune substantially broader than the first stage. A distinct advantage to be derived from this characteristic is that the fidelity, or quality of signal reproduction, is then unimpaired, because the admitted side bands of a single stage may be at least sixty-four thousand (64,000) cycles wide, on each side of the resonance peak, at fifty per cent (50%) of maximum amplification. The resultant resonance curve of the entire multi-stage receiver is the product of the resonance curves of all of the stages. This resultant curve may therefore have the same general characteristics as the resonance curve of receivers employing fewer stages of increased sharpness per stage. Another pronounced advantage introduced by the broad tuning is that the high-frequency transformers and tuning condensers may be manufactured within readily obtained commercial tolerances, and at the same time be capable of satisfactory operation with uni-controlled condenser adjustments.

The curves shown in Fig. 5 represent the amplification per stage at resonance, (a) of a typical transformer as heretofore employed in high-frequency amplifiers including vacuum tubes; and (b) of a transformer, in accordance with the present invention, employed in combination with a vacuum tube, as shown in Fig. 3. It is apparent from curve "B" that, since the losses purposely introduced are a function of the frequency, the voltage amplification per stage is, by means of this invention, maintained at a high degree and very nearly constant throughout the operating frequency range. Previous to the present invention it was the practice to minimize so far as practicable all of the losses in tuned high-frequency interstage coupling transformers; but it has been found that such transformers introduce the very undesirable feature of a large difference in voltage amplification between the upper and lower limits of the operating frequency range as shown in curve "A". Furthermore, the extremely high degree of amplification obtained at the low wave-length end of the range introduced a great tendency toward undesired oscillations. In order to lessen this tendency, it was the practice to reduce the number of primary turns of the transformer, the net result being a lower average amplification. On the other hand, the present invention allows of a comparatively large number of primary turns whereby an increased average amplification is attained.

The improved amplification characteristic and the desired broadness of tuning are realized in this invention through the introduction of capacity and dielectric losses which appear in the interstage high-frequency transformers such as those represented in Fig. 3 by reference characters T_2 , 130

T_3 and T_4 . These losses result from utilizing a small form upon which to wind the wire, as, for example, a cylindrical insulating tube two inches in diameter; by using wire of 6 rather small gauge, for example No. 30, American wire gauge, so that the turns are 10 closely together; by winding together the turns comprising the neutralizing coil represented in Fig. 3 as 7, 10 and 18, respectively, and the 15 turns of the corresponding primary coils 6, 9 and 12, respectively, on the same form so that the turns of the neutralizing coil and the primary of the same transformer lie alternately and adjacent on the form; and by employing an unusually large number of 20 primary turns, as represented at 6, 9 and 12, respectively. It has been discovered that the 25 mentioned dielectric loss may be regulated by varying the spacing between the turns of the primary and neutralizing windings; that is, by regulating the number of turns per inch of these windings, in order to control the degree of amplification at different frequencies, so that the amplifier effects substantially uniform amplification throughout the broadcast range. In the actual embodiment described herein, the secondary windings 8, 10 and 14 of the transformers T_2 , T_3 and T_4 were each wound on a form $2\frac{1}{4}$ inches 30 in diameter, the secondary winding of each transformer being mounted with its form surrounding the form supporting the primary and neutralizing windings thereof.

At least five objects are attained by this 35 construction: first, more nearly complete neutralization of the combined inter-electrode and between-the-leads capacity is realized by the extremely close coupling between the two coils in question; second, high amplification, or gain, per stage, resulting from the large number of primary turns; third, the introduced capacity and dielectric losses result in the desired broad and easy tuning; fourth, since these losses are effective as resistance in the coupling transformers and 40 vary in proportion to the inductance-to-capacity ratio as the tuning capacity is varied, the degree of amplification is reduced at the higher frequencies, and consequently 45 the amplification characteristic is nearly uniform over the entire operating frequency range of the high-frequency system; and fifth, the coils being physically small, allow 50 of the use of a containing cabinet of convenient proportions. The arrangement of 55 the common condenser shaft parallel to the control panel also assists in allowing of a conveniently proportioned cabinet. It is believed to be obvious that many of the improvements introduced by this invention may 60 with good effect be embodied in transmitting, or in other apparatus, in which a multistage high-frequency amplifier is included.

The constants of the principal components 65 of the radio receiver herein illustrated and

described are given below by way of example, but it is to be understood that they are provided only in order that this description of a typical embodiment may be more nearly complete, no limitation being thereby intended: 70

T_1 —64 turns, #20 A. W. G. enameled copper wire spaced 16 turns to the inch on a threaded, 3 inch diameter, hard rubber cylinder; antenna and grid connection at 32 75 turns.

T_2 , T_3 , T_4 —primary 20 turns, #30 A. W. G. double silk covered wire on 2 inch cylinder; secondary 63 turns #30 A. W. G. double silk covered wire on $2\frac{1}{4}$ inch cylinder; neutralizing winding 20 turns, #30 A. W. G. double silk covered wire wound adjacent and parallel to the primary turns. 80

$C_{1,2,3,4}$ —500 micro-microfarads, maximum.

$C_{2,3,4}$ —15 micro-microfarads, maximum.

$C_{n1,2,3}$ —15 micro-microfarads, maximum.

$C_{t1,2,3,4}$ —1 microfarad.

$C_{p1,2,3}$ —1 microfarad.

$C_{p4,5}$ —3000 micro-microfarads.

C_g —250 micro-microfarads.

16, 17—1 microfarad.

R —6 ohms.

R' —20 ohms.

$R_{2,3,4}$ —200 ohms.

R_5 —10,000 ohms.

R_g —2 megohms.

$L_{1,2,3,4}$ —100 microhenries, and 1 ohm D. C. resistance.

I claim:

1. In an amplifier, a plurality of amplifying stages; each stage including at least one high-frequency winding, a variable condenser and a vacuum tube; an input circuit for each vacuum tube including one of said windings tuned by one of said condensers; an output circuit for each vacuum tube including a winding coupled to a succeeding vacuum tube; a metal box-shield enclosing said winding, said variable condenser and said vacuum tube of each stage; a conducting metal shaft extending through said metal box-shields for operating several of said variable condensers simultaneously; and short electrical connections between said metal shaft and said box-shields substantially 100 at the points where said shaft passes through the walls of said box-shields whereby stray couplings due to said common metal shaft are 105 prevented.

2. In a high-frequency vacuum tube amplifier comprising more than two stages, means for coupling the first stage thereof to an antenna system, said first stage being designed to tune sharply to all frequencies within a predetermined band, individual means for 110 tuning said first stage, means for successively coupling a plurality of the remaining stages in cascade, each of said plurality of remaining stages being designed to tune broadly 115 (as compared to the sharpness of tuning of 120

85

90

95

100

105

110

115

120

125

130

said first stage) at all of the frequencies within said predetermined band, and uni-controlled means for tuning simultaneously all of said plurality of remaining stages.

- 5 3. In a high-frequency vacuum tube amplifier comprising more than two stages, means for coupling the first stage thereof to an antenna system, said first stage being designed to tune sharply to all frequencies within a
10 predetermined band, individual means for tuning said first stage, means for successively coupling a plurality of the remaining stages in cascade, each of said plurality of remaining stages being designed to tune broadly
15 (as compared with the sharpness of tuning of said first stage) at all of the frequencies within said predetermined band, means for preventing undesirable oscillations in each of said stages whereby a high degree of faithful
20 amplification throughout the frequency range of the amplifier is attained and uni-controlled means for tuning simultaneously each of said plurality of remaining stages.

4. In a radio receiver, a plurality of high-frequency amplifying stages each including a vacuum tube together with tunable coupling apparatus, metal box-shields each enclosing a vacuum tube and associated apparatus comprising one of said stages, said box-shields
25 each being effective to shield the apparatus enclosed therein against interstage coupling, each of said box-shields having an aperture therein large enough to permit the insertion and removal of a vacuum tube, and metal
30 caps each adapted to form a closure for one
35

of said apertures, said metal caps being designed to be removably secured to their respective box-shields and, when in position, to completely close said apertures and to make electrical contact with their respective
40 box-shields, the arrangement being such that each amplifying stage is completely shielded while at the same time permitting easy access for removal and replacement of the vacuum tubes.
45

5. In a radio receiver, a plurality of high-frequency amplifying stages each including a vacuum tube together with tunable coupling apparatus, metal box-shields each enclosing a vacuum tube and associated apparatus comprising one of said stages, said box-shields each being effective to shield the apparatus enclosed therein against interstage coupling, each of said box-shields having an aperture therein large enough to permit the insertion and removal of a vacuum tube, the arrangement being such that when said vacuum tube is in its operating position the free end portion thereof projects through said aperture, and a metal cap for each of
50 said box-shields, each of said metal caps being adapted to be frictionally secured to its box-shield in such a way as to be readily removable and when in place to form a complete closure for said aperture whereby to
55 complete the shielding of the apparatus enclosed within the box shield.

In testimony whereof I affix my signature.

JOHN F. DREYER, JR.
